UNITED STATES PATENT OFFICE

148,706

DESIGN FOR A COMBINATION STROLLER, ROCKER, SLED, AND WALKER

Charles V. Kenney, Chicago, Ill.

Application October 24, 1946, Serial No. 134,196

Term of patent 14 years

(Cl. D14—14)

To all whom it may concern:

Be it known that I, Charles V. Kenney, a citizen of the United States, residing in the city of Chicago, county of Cook and State of Illinois, have invented a new, original, and ornamental Design for a Combination Stroller, Rocker, Sled, and Walker, of which the following is the specification, reference being made to the accompanying drawing, forming a part thereof.

Fig. 1 is a perspective view of a combination stroller, rocker, sled, and walker, showing my new design when used as a stroller; and

Fig. 2 is a similar perspective view of the same when used as a rocker or sled.

I claim:

The ornamental design for a combination stroller, rocker, sled, and walker, as shown.
CHARLES V. KENNEY.
